UNITED STATES PATENT OFFICE.

JOHN J. HAGGENJOS, OF ST. LOUIS, MISSOURI.

DESIGN FOR A GRAVE MARKER.

Application filed July 9, 1925. Serial No. 14,032. Term of patent 14 years.

To all whom it may concern:

Be it known that I, JOHN J. HAGGENJOS, a citizen of the United States, residing at 601 Red Bud Avenue, in the city of St. Louis, in the State of Missouri, have invented a new, original, and ornamental Design for Grave Marker, of which the following is a specification, reference being had to the accompanying drawing, forming part thereof.

Figure 1 is a view of the top face of the grave-marker;

Figure 2 is a front elevation of the marker;

Figure 3 is an end elevation thereof; and Figure 4 is a perspective view.

I claim:

The ornamental design for a grave marker, as shown.

JOHN J. HAGGENJOS.
